SKATE STOP

Arthur Lieberman, South Bend, Ind.

Application June 26, 1941, Serial No. 399,819

5 Claims. (Cl. 289—11.20)

This invention relates to a skate stop adapted to be applied to a skater's shoes and to serve as means by which a person on roller skates may quickly come to a stop while skating.

The primary object of the invention is to provide a novel, simple and inexpensive device which is readily attachable to a skate shoe to serve as an effective brake or stop for skaters.

A further object is to provide a skate stop which may be solidly secured to a skate shoe to withstand the stresses applied thereto in braking.

A further object is to provide a skate stop formed of hard rubber shaped to correspond to the shape of the toe portion of the shoe, and having a front portion sufficiently thick to permit contact with a rink surface without contact of the shoe with said surface, and a thinner rear portion to enlarge the bearing area of the stop with the sole of a shoe and to facilitate the use of ample securing means to solidly and securely hold the stop to the shoe.

Other objects will be apparent from the description, drawing, and appended claims.

In the drawing:

Fig. 1 is a diagrammatic side view of a skate and skate shoe illustrating my skate stop applied to the shoe.

Fig. 2 is a bottom plan view of the skate stop.

Fig. 3 is a side view of the skate stop.

Fig. 4 is a rear end view of the skate stop.

Fig. 5 is a longitudinal vertical sectional view of the skate stop taken on line 5—5 of Fig. 2.

Fig. 6 is a sectional view corresponding to Fig. 5 and illustrating a modified embodiment of the invention.

Fig. 7 is a sectional view corresponding to Fig. 5 and illustrating another modified embodiment of the invention.

Fig. 8 is another view corresponding to Fig. 5 and illustrating another embodiment of the invention.

Referring to the drawing, which illustrates the preferred embodiment of the invention, the numeral 10 designates a skate shoe having a sole 11 and a heel 12. The top plate 13 of a roller skate 14 is fixedly secured to the sole and heel of the shoe. My skate stop 15 is illustrated in Fig. 1 in its operative relation to the skate shoe.

Skate stop 15 is formed of rubber hard enough to resist deforming thereof under stress but sufficiently soft to have an effective braking action without danger of breakage due to brittleness when subjected to stress. The stop 15 has a curved front edge 16 and rearwardly diverging side edges 17, whereby it substantially conforms

to the shape of the toe portion of the sole of a shoe. The front portion 18 of the stop is of a substantial thickness, whereby, when the skater tilts his foot about the forward wheels of his skate, front portion 18 may be brought into contact with the rink surface at an angle substantially less than would be required to bring the front of the sole 11 of the shoe into contact with the rink surface. I have found that the preferred thickness of portion 18 is approximately one inch, or a dimension substantially one-third the distance from the skating surface to the bottom of the shoe sole. The thickened portion 18 extends not more than one-half the total length of the skate stop, and is defined at its rear edge by a rearwardly upwardly inclined face 19. The rear portion 20 of the stop is of a reduced thickness, preferably about one-half the thickness of the front portion 18 of the stop. The rear edge 21 of the stop is preferably formed by a flat rearwardly upwardly inclined surface 21.

The top face of the stop is provided with a deep concavity 22 whereby the thickness of the skate stop is less adjacent its center than adjacent its edges 17 and 18. The concavity 22 extends to the rear edge 21 of the skate stop as best illustrated in Fig. 5. The thick front portion 18 of the skate stop has a plurality of preformed holes or recesses 23 formed therein adjacent its front margin. Holes 23 are axially aligned with metal washers 24 imbedded within the rubber and serving as stops for the heads of nails employed to secure the device to the sole of a shoe. I have found that for best results it is desirable to provide a nail hole 23 at the front center portion of the enlargement 18 and at least two other nail holes arranged in complementary relation to the first at opposite sides of the portion 18. Similar preformed openings 25 are formed in the reduced thickness portion 20 of the skate stop adjacent opposite sides thereof.

The skate stop is secured to the sole of the shoe by nailing, in the manner well understood in the art. Care must be taken to position the stop in balanced or centered relation with respect to the longitudinal center line of the shoe sole. The stop should extend substantially to the front edge of the shoe sole, as illustrated in Fig. 1. A nail is driven in each of the nail holes 23 and 25. The rubber of which the stop is formed is of sufficient flexibility to permit the concave top surface 22 of the stop to be forced into full bearing engagement with the bottom of the sole 11 of the shoe.

The use of at least five nails to secure the

stop to the shoe sole insures that the same will be solidly and firmly mounted upon the sole in a manner to withstand the stresses applied thereto in use. Note in this connection the use of three nails at the front or toe portion 18 where the greatest stress occurs. The rearward upward inclination of the rear wall 19 of the front portion 18 of the stop is also important as a means to reinforce this thickened portion 18 of the stop against the forces which are applied thereto.

In order to provide an effective skate stop, it is desirable that the thickness thereof shall be sufficient to permit contact thereof with the rink surface without requiring tilting of the skate and the foot at an angle which makes the use thereof awkward, yet the thickness must not be so great that the stop interferes with the full free movement of the foot in skating. The instant construction with its thickened portion 18 and rear comparatively thin portion 20 permits the formation of the front working portion 18 of the stop of ample thickness to be effective for its purpose. It will be observed in this connection that the stresses which are applied to the stop during use thereof have longitudinal and downward components, that is, the stresses are applied at an angle to the top and bottom faces of the stop. The use of reduced portion 20 provides a foundation or bearing surface of sufficient area and size to permit the stop to effectively withstand the longitudinal component of the force applied in braking or stopping. The number and location of the securing nails withstand the downward stress, together with the rigidity of the member and its tendency to resist flexing.

While the preferred embodiment of the invention is illustrated in Figs. 2 to 5, inclusive, it will be understood that various modified embodiments are possible. Thus, Fig. 6 illustrates a modified embodiment wherein the longitudinal contour of the stop is rounded, especially at part 26 between the front and bottom of the portion 18.

Fig. 8 illustrates another embodiment wherein the front of the stop is rearwardly downwardly tapered at 27.

The Fig. 7 embodiment illustrates a construction wherein the thickened portion 28 is smaller than the portion 18 of the preferred embodiment, and is provided with a rear edge 29 which is inclined upwardly and forwardly so that the longitudinal dimension of part 28 is greater at its bottom than at its top. The length of part 28 is short enough to render said part more flexible than the remainder of the stop, so that it may flex as illustrated in dotted lines at 30 when used.

Except as herein specifically mentioned, each of the embodiments 6 and 7 and 8 corresponds in other respects to the preferred embodiment.

I claim:

1. A skate stop adapted to be secured to the toe portion of the sole of a shoe and comprising a body formed of rubber of a hardness sufficient to resist distortion under stress but capable of being flexed without breaking, said body having a front edge curved to substantially conform with the toe of a shoe and merging with rearwardly diverging sides, a portion of said body at the front thereof and extending substantially midway of the body length being of a substantially uniform thickness substantially greater than the thickness of the rear portion, said body having a plurality of nail-receiving openings in its front portion, and having additional nail-receiving openings in its rear portion.

2. A skate stop adapted to be secured to the toe portion of the sole of a shoe, comprising a body formed of rubber, said body being curved at its front and diverging rearwardly from said curve, the front portion of said body being of a thickness substantially twice that of the rear portion and merging therewith at a vertically tapered intermediate portion, said body having a plurality of nail-receiving openings in each of its front and rear portions.

3. A skate stop comprising a body of a shape substantially conforming to and adapted to be secured to the toe portion of the sole of a shoe, said body having a thick flat front portion, a comparatively thin substantially flat rear portion and a vertically tapered intermediate portion, said front portion being of a thickness approximately one-third of the spacing of the shoe sole above the skating surface, the rear edge of said front portion extending parallel and adjacent to an inclined plane tangential to the lower front peripheral portions of the front wheels of the skate and passing through the upper front edge of the stop body.

4. A skate stop as defined in claim 3, wherein said body has a plurality of nail-receiving openings therein adjacent its front and side margins and including openings at the center and opposite sides of said front portion.

5. A skate stop comprising a rubber body of a shape substantially conforming to the shape of the toe portion of a shoe and adapted to be secured thereto, said body having a front portion of substantially greater thickness than the rear portion thereof and defined in part by an upwardly forwardly inclined rear face, said front portion being of a comparatively short length to accommodate limited flexing thereof, the major portion of said body being substantially rigid.

ARTHUR LIEBERMAN.
